UNITED STATES PATENT OFFICE.

HOWARD M. DODGE, OF AKRON, OHIO, ASSIGNOR TO ERNEST F. MARCHA, OF CLEVELAND, OHIO.

INNER TUBE.

1,414,331.

Specification of Letters Patent. Patented Apr. 25, 1922.

Application filed September 11, 1920. Serial No. 409,726.

To all whom it may concern:

Be it known that I, HOWARD M. DODGE, a citizen of the United States, and resident of Akron, in the county of Summit and State 5 of Ohio, have invented certain new and useful Improvements in Inner Tubes, of which I hereby declare the following to be a full, clear, and exact description, such as will enable others skilled in the art to which it 10 appertains to make and use the same.

The objects of the invention are to provide an improved inner tube for a pneumatic tire, which is so constructed as to resist leakage when punctured and is also so constructed 15 as to resist collapse when deflated, thus making the tube more durable, efficient and practical for general use.

The invention comprises an inner tube corrugated or fluted throughout substantially the greater part of its longer circumferential surfaces, and molded to assume a smaller diameter than that of the inner circumference of the casing, and after it has 20 been inflated therein it assumes the full diameter of the inner surface of the casing, with the outwardly projecting flutes or ribs 25 engaging with the inner circumference of the casing.

When the inner tube is subjected to further 30 internal pressure the inwardly projecting ribs or flutes will be flattened down and the material composing them will be subjected to compression laterally or in the direction of the short circumference of the tube and 35 the material will be condensed so that when punctured by a sharp object, such as a nail or spike, it will close as soon as the object is removed and the tire will retain its ability to retain air under pressure, without leakage.

40 The invention also includes the rectangular recesses formed between the external flutes or ribs of the inner tube by means of transverse, externally projecting ribs (preferably hollow). When the longitudinal and 45 transverse projections thus formed are compressed against the casing a partial vacuum will be created between them, which resists deflation of the tube and prevents the tube from shifting irregularly about in the casing, and increases its efficiency and durability.

The invention is illustrated in the accom-

panying drawings, hereinafter further described, and specifically pointed out in the claims.

It also includes means for creating a local lateral pressure at the edges of the rim side of the inner tube, which will prevent the beads or rim edges of the outer casing from becoming loose in the flanges of the rim, or 55 escaping therefrom.

In the accompanying drawings, Fig. 1 is a transverse section of a tire casing and inner tube, showing the preferred form of the invention before inflation, and, in dotted lines, after inflation. Fig. 2 is a plan of a portion of the inner tube; Fig. 3 is a longitudinal section thereof; Figs. 4, 5, 6, and 7 show modified forms of construction of the 60 inner tube.

In these views, A represents the casing; B represents the inner tube, which, when deflated, is of smaller diameter than that of the circumference of the inner surface, C, of the casing.

The inner tube is longitudinally fluted or corrugated on both inner and outer surfaces, the thickness of the material remaining substantially the same throughout to prevent 70 irregular compression thereof when the tube is inflated.

These corrugations preferably extend around the greater part of the transverse circumference of the tube, a small portion being left smooth at D, where it comes in 75 contact with the filler piece, E, which closes the gap between the rim edges of the casing.

The corrugations are equally spaced about the periphery of the tube, and are not deeply indented but form alternate longitudinal annular grooves, F, and longitudinal annular projections, G, the material embodied therein having such an amount of total superficial area that when expanded under internal pressure from the collapsed condition 80 the inner tube will exactly correspond in diameter with the inner circumference of the casing, with the outwardly projecting flutes or ribs in contact with the casing and the inwardly projecting corrugations or flutes extending more nearly to their full 85 width, but still preserving their arcuate form.

Upon the further application of internal

pressure the inwardly extending corrugations are pressed flat against the casing and the material therein is compressed in a lateral direction, thus condensing it to such an extent that when pierced by a sharp object and the object removed, it will close the opening and prevent the leakage of the compressed air contained therein.

It is also much less susceptible to puncture when compressed in this manner than if it were stretched tightly by inflation in the ordinary manner.

Transverse corrugations or hollow ribs H connecting the longitudinal ribs also provide the same useful result, and when expanded make contact with the inner surface of the casing.

Further, when subjected to expansion the arched material lying between these ribs will become flattened and upon further inflation of the tubes will be compressed longitudinally of the tube and condensed in the same manner as the circumferential ribs previously described. This action subjects the material to compression in two directions, both laterally and longitudinally, and thickens it to a certain extent at all points of the corrugated surfaces.

An important advantage obtained from the rectangular recesses thus formed in the outer surface of the inner tube is found in the fact that when the tube is flattened against the casing a partial vacuum will be produced at the position of each recess, which will have a tendency to grip the casing and to resist deflation of the tube.

Also, the transverse ribs and vacuum producing depressions will have a tendency to prevent longitudinal or other shifting of the tube within the casing.

At I, Fig. 1, are shown longitudinal flutings which are positioned closely adjacent to the rim edges, J, J, of the outer casing. These flutings, when expanded and afterwards compressed against the sides of the filler piece and bead or rim edges of the casing, force these edges into such close engagement with the flanges, K, K, of the rim that the danger of their becoming detached therefrom is reduced to the minimum. The central portion of the filler piece, E, is also pressed tightly into the space between the rim edges of the casing by the narrow uncorrugated portion, D, of the inner tube.

In Fig. 4, the transverse flutings, H, are shown opposite but diagonal; in Fig. 5, they are staggered; in Fig. 6, transverse flutings, H, are joined by longitudinal flutings, G and H', and in Fig. 7, the longitudinal flutings, G, are formed in sinuous lines, and are joined by spaced, transverse flutings H. Other variations in the combination and arrangement of the flutings can be arranged within the scope of the claims.

Having described the invention what I

claim as new and desire to secure by Letters Patent is:

1. The combination with a casing, of a pneumatic inner tube therefor, said tube provided with annular longitudinally directed hollow flutes alternating with annular recesses, and also provided with transverse hollow ribs connecting adjacent flutes across said recesses, the recesses included between said flutes and ribs, forming vacuum chambers in contact with the inner surface of said casing when said tube is fully inflated.

2. The combination with a casing, of a pneumatic tube therefor, said tube provided with longitudinally directed annular projections alternating with annular recesses on both inner and outer surfaces, and with narrow, staggered, transverse, hollow projections connecting adjacent longitudinal projections on their outer surfaces, and provided with a narrow, smooth, annular, projecting surface upon the rim side, the normal diameter of said tube being less than the normal diameter of the inner surface of said casing, said longitudinal and transverse projections enclosing vacuum producing surfaces when said tube is inflated into contact with the inner surface of said casing.

3. The combination with a casing of a pneumatic tube therefor, said tube provided with annular longitudinally directed hollow flutes alternating with annular recesses, and also provided with transverse hollow ribs connecting adjacent flutes across said recesses, the recesses included between said flutes and ribs forming vacuum chambers in contact with the inner surface of said casing when said tube is fully inflated, and the rim side of said tube being normally straight in cross section for a distance greater than the distance between the rim edges of the casing, whereby the rim side of the tube when inflated wedges apart the rim edges of the casing.

4. The combination of a casing adapted to be mounted on a rim with the space between the rim edges of the casing narrowing towards the rim, of a pneumatic tube having a normal diameter less than the internal diameter of the casing, the tube being normally corrugated so that its external surface is greater than the internal surface of the casing, and the tube having a rim side normally straight in cross section for a distance greater than the distance between the rim edges of the casing, whereby when the tube is inflated and the corrugations smoothed out against the casing, the tube walls will be under lateral compression and the flat rim side will wedge apart the rim edges of the casing.

5. The combination of a casing adapted to be mounted on a rim, a filler adapted to lie against the rim between the rim edges of the casing and having flaps lying against

said rim edges of the casing, the flaps decreasing in thickness as they recede from the rim, and a pneumatic tube having a normal diameter less than the internal diameter of 5 the casing, a normal outer surface greater than the inner surface of the casing, and a rim side normally straight in cross section for a distance greater than the distance between the flaps of the filler at the rim and 10 less than the distance between the flaps at

their outer edges, whereby when the tube is inflated within the casing its walls are under lateral compression and the rim side is wedged out against the flaps of the filler.

In testimony whereof, I hereunto set my 15 hand this 2nd day of Sept. 1920.

HOWARD M. DODGE.

In presence of—

Wm. M. MONROE,
CHAS. C. GOLDMAN.
